(57) **CLAIM**

I claim the ornamental design for a portable vehicle power source and air pump, as shown and described.

DESCRIPTION

FIG. 1 is a front side top view of a portable vehicle power source and air pump according to an embodiment;

FIG. 2 is a back side top view of the portable vehicle power source and air pump;

FIG. 3 is a front view of the portable vehicle power source and air pump;

FIG. 4 is a back view of the portable vehicle power source and air pump;

FIG. 5 is a left-side view of the portable vehicle power source and air pump;

FIG. 6 is a right-side view of the portable vehicle power source and air pump;

FIG. 7 is a top view of the portable vehicle power source and air pump; and,

FIG. 8 is a bottom view of the portable vehicle power source and air pump.

The broken lines shown in the drawings are for illustrative purposes only and form no part of the claimed design. The several photographic views, if any, are informal photographs being submitted pursuant to M.P.E.P. § 1503.02(V).
